REVERSING TOOL

Walter L. Church, Houston, Tex.

Application October 10, 1952, Serial No. 314,133

6 Claims. (Cl. 255—35)

1
This invention relates to a reversing tool and more particularly to a tool for use in the recovery of stuck drill pipe, tubing, or the like, from wells, such as oil wells.

In removing stuck pipe from oil wells, as heretofore practiced, it has been customary to employ a back-off or reversing tool in conjunction with grapping means by which an operating string is connected with the pipe to be recovered, and such tools have usually been provided with means operable by manipulation of the operating string to anchor one part of the tool to a surrounding well casing, so that a reverse rotation can be imparted to the grapping means to unscrew a joint in the stuck pipe. The anchoring means usually employed has consisted of a grapple shoe with wedging means disposed below the same to move the shoe into gripping engagement with the casing upon the exertion of an upward pull of the operating string. Such means, however, has proven to be very troublesome in operation, exerting a pull on the same, which often results in faulty operation or in some cases in loss of the entire tool in the well.

The present invention has for its chief object the overcoming of the above disadvantages by the provision of a reversing tool having casing-gripping means which is operable independently of any movement of the operating string, for anchoring one part of the tool to a surrounding well casing.

Another object of the invention is the provision of a reversing tool which is readily rotatable with the operating string in either direction, and which is operable upon the application to the tool of pressure in the string and rotation of the string to rotate the grapping means in the opposite direction to unscrew a joint of the pipe to be recovered, or upon release of the pressure in the string from the tool and rotation of the string to rotate the tool in the same direction, as the string, to enable the tool to be readily disconnected from the stuck pipe, in the event that the stuck pipe cannot be otherwise released, or it becomes desirable to remove the tool with the operating string for some other reason.

A further object of the invention is to provide a reversing tool which is rotatable in one direction with the operating string and having means operable by fluid pressure for causing the tool to rotate in the opposite direction relative to the operating string upon continued rotation of the operating string in the same direction.

Another object of the invention is the provision of a reversing tool embodying pressure fluid operable means for engaging a surrounding well-casing to anchor the tool in the casing.

A still further object of the invention is to provide a reversing tool of the type referred to, which is of simple design and rugged construc-

tion, capable of long withstanding the hard usage to which devices of this character are customarily subjected.

The above and other important objects and advantages of the invention will best be understood from the following detailed description, constituting a specification of the same, when taken in conjunction with the annexed drawings, wherein—

10 Figure 1A is a vertical, central, cross-sectional view of the upper portion of a reversing tool constructed in accordance with the invention;

Figure 1B is a vertical, central, cross-sectional view of the lower portion of the same;

15 Figure 2 is a cross-sectional view, taken along the line 2—2 of Figure 1A, looking in the direction indicated by arrows; and

Figure 3 is a cross sectional view taken along the line 3—3 of Figure 1B, looking in the direction indicated by the arrows.

Referring now to the drawings in greater detail, the reversing tool has an upper tubular member 10 and a lower tubular member 12, the upper member being provided with a reduced lower end portion 14 which is rotatably fitted into the upper end of the lower member. The reduced portion 14 has an external annular groove 16 therein, in which suitable packing, such as an O-ring, indicated at 18 is disposed, which forms a fluid tight seal between the upper and lower members. Opposed annular grooves may also be formed in the reduced portion 14 and in the interior of the upper end portion of the lower member, these grooves forming raceways 20 and 22, in which suitable bearings, such as ball bearings are disposed, whereby the members are rotatably secured together.

The lower tubular member 12 has internal gear teeth 24 therein, which extend from the lower end of the reduced portion 14 of the upper member 10 to a point short of the lower end of the lower member.

The lower end portion of the upper tubular member 10 also has a tubular extension 26, of reduced external diameter below the portion 14, and in which longitudinal openings 28 are formed for the reception of gears 30 whose teeth mesh with the teeth 24 of the lower tubular member 12.

A tubular connection 32 is threadably secured to the lower end of the lower tubular member 12, which connector has a pin 36 formed with an external left hand thread 38. The inner end of the connector 32 forms a valve seat 40 for a pressure fluid operable element 42 slideably disposed in the lower tubular member, and whose lower end portion is of reduced diameter and has a rounded end 44 forming a valve adapted to seat on the seat 40. At its upper end the element 42 is provided with external gear teeth 46 which mesh with the internal teeth 24 of the lower

tubular member. There is an upwardly opening recess 48 in the upper end of the element 42 which is provided with internal gear teeth 50, and a resilient element, such as a coil spring 52, surrounds the lower portion of the element 42 in engagement at one end with the connector 32 and at the other end bears against a downwardly facing external shoulder 54 formed on the upper portion of the pressure fluid operable element 42 to urge the same upwardly.

An inner tubular mandrel 56 is rotatably mounted in the upper tubular member, and extends somewhat below the lower end thereof, the lower end portion of the mandrel being provided with external gear teeth 58 which mesh with the teeth of the gears 38. The teeth 58 extend below the lower end of the upper tubular member 10 in position for interengagement with the internal teeth 50 in the recess 48 of the pressure operable element 42. When the latter is in uppermost position, this element will then rotate with the mandrel and will in turn rotate the lower tubular member 12 therewith.

The upper member 10 is conveniently provided with internal annular grooves 60 and 62, in which suitable packing means, such as O-rings indicated at 64 and 66, respectively, may be disposed, to form a fluid tight seal between the mandrel 56 and the upper member. The mandrel 56 has an externally enlarged portion 68, adapted to be rotatably received in a counterbore 70 formed in the upper end of the upper tubular member, and a tubular nut 72 is threadably secured in the counterbore 70 above the enlargement 68 and engageable with the upper face thereof to retain the mandrel in position in the tool. Suitable coupling means, such as that indicated at 74 is threadably attached to the upper end of the mandrel, and by which the same may be secured to the lower end of an operating string of pipe for rotation therewith.

The upper tubular member 10 has a number of externally opening recesses 76 therein, in which radially movable casing-engaging slips 78 are positioned, each of the slips having cut-away portions 80 forming outwardly facing shoulders 82, which are engageable beneath the heads of screws 84 carried by the tubular member 10, to limit outward movement of the slips.

Positioned in the recesses 76 inwardly of the slips 78 and in engagement with the inner faces thereof, there are the resilient elements 86, which are in sealing contact with the upper member 10 about the recesses.

Each of the recesses 76 is in communication with the base 88 of the mandrel 56 through a suitable opening 90 whereby pressure fluid in the mandrel may enter the recesses beneath the resilient elements 86 to force the slips outwardly into gripping engagement with a surrounding well casing to anchor the tool in the casing.

The gears 38 are retained in the openings 28 in the lower end portion of the upper tubular member 10 by means of a ring 92 or the like suitably secured to the lower end of the upper member in any convenient manner, as by welding or by the use of suitable fastening means not shown.

In making use of the invention, constructed as described above, the coupling 74 is screwed on to the lower end of an operating string and a suitable grapple is attached to the pin 32 by the left-hand threads 35, and the tool is then lowered into the well to engage the grapple with the pipe to be removed. The member 42, in this condition of the tool is held in its uppermost position by

the spring 52, so that the internal teeth 50 of this member are in interengagement with the external teeth 58 of the mandrel 56, and because of the interengagement of the external teeth 46 of the member with the internal teeth 24 of the lower tubular member 12, the grapple will rotate with the operating string and will turn in the same direction.

Should it be desired to rotate the tool in a direction opposite the direction in which the operating string is rotated, the pressure of fluid in the operating string is applied through the bore 88 of the mandrel 56, to move the pressure operable member 42 into engagement with the seat 40 and close the tool against downward flow of the fluid therethrough. The pressure within the bore 88 is then transmitted, by way of the openings 90, to the flexible elements 86, to actuate the slips 78 into gripping engagement with the surrounding well casing to anchor the upper tubular member 10 in the casing. With the upper member 10 locked in the casing and the pressure operable member 42 in the lowermost position, as seen in Figure 1B, rotation of the mandrel 56 with the operating string causes rotation of the gears 38, which in turn rotate the lower member 12 in the opposite direction to the direction of rotation of the string.

The tool may be readily released from the casing upon relief of the fluid pressure in the operating string, whereupon the pressure operable member 42 is returned to its uppermost position by the spring 52, and the tool is then in condition to rotate the grapple in the same direction in which the string is rotated.

By the use of the tool in the manner described it becomes possible to readily unscrew a stuck pipe and recover the same from the well, and in the event that the stuck pipe cannot be uncoupled and the grapple will not release, it is then possible to reverse the rotation of the tool and disconnect the same from the grapple for recovery with the operating string.

It will thus be apparent that the invention as described above provides a reversing tool of simple design which is capable of use in a wide variety of operations, wherever the reversal of the direction of rotation of an operating string or the like may be desirable.

While the invention has been disclosed in connection with a specific embodiment of the same it will be understood that this is intended by way of illustration only, and that numerous changes can be made in the construction and arrangement of the various parts, without departing from the spirit of the invention or the scope of the appended claims.

Having thus clearly shown and described the invention, what is claimed as new and desired to secure by Letters Patent is:

1. A reversing tool comprising, a tubular mandrel, means connecting the mandrel in fluid flow communication with an operating string for rotation with the string, an upper tubular member rotatably connected to the mandrel, a lower tubular member carried by the mandrel in communication therewith and rotatable relative to the upper member, casing-engaging means on the upper member, means operable by the pressure of fluid in said mandrel for actuating said casing-engaging means into engagement with a surrounding well casing to anchor said upper member against rotation in the casing, internal gear teeth in said lower member, external gear teeth on said mandrel, gear means carried by said upper

member in intermeshing engagement with said gear teeth to cause said mandrel to rotate said lower member in a direction opposite to the direction of rotation of the mandrel when said casing-engaging means is actuated, and means intermeshingly engageable with said gear teeth to cause said mandrel to rotate said lower member in the direction of rotation of the mandrel when said casing-engaging means is released.

2. A reversing tool comprising, a tubular mandrel, means connecting the mandrel in fluid flow communication with an operating string for rotation with the string, an upper tubular member rotatably carried by the mandrel, a lower tubular member in communication with said mandrel, means rotatably connecting said lower member to said upper member, casing-engaging means on the upper member, means operable by the pressure of fluid in said mandrel for actuating said casing-engaging means into engagement with a surrounding well casing to anchor said upper member against rotation in the casing, interengageable means on the mandrel and said lower member and operable by the mandrel upon actuation of said casing-engaging means to cause said lower member to rotate in a direction opposite to the direction of rotation of the mandrel, and pressure fluid operable means on the lower member interengageable with said mandrel and said lower member and operable by said mandrel upon release of said casing-engaging means to cause said lower member to rotate in the direction of rotation of said mandrel.

3. A reversing tool comprising, a tubular mandrel, means connecting the mandrel in fluid flow communication with an operating string for rotation with the string, an upper tubular member rotatably connected to the mandrel, a lower tubular member carried by the mandrel in communication therewith and rotatable relative to the upper member, casing-engaging means on the upper member, means operable by the pressure of fluid in said mandrel for actuating said casing-engaging means into engagement with a surrounding well casing to anchor the upper member against rotation in the casing means interengageable with the lower member and mandrel and operable by rotation of the mandrel in one direction to rotate said lower member in the opposite direction upon actuation of said casing-engaging means, and means releasably interengageable with the mandrel and said lower member and operable by rotation of the mandrel in said one direction to rotate the lower member in said one direction upon release of said casing-engaging means.

4. A reversing tool comprising a tubular mandrel, means connecting the mandrel in fluid flow communication with an operating string for rotation with the string, an upper tubular member rotatably carried by said mandrel, a lower tubular member in communication with the mandrel, means rotatably connecting said members, casing-engaging means on the upper member, means on the upper member operable by the pressure of fluid in the mandrel for actuating said casing-engaging means into engagement with a surrounding well casing to anchor said upper member against rotation in the casing, gear means rotatably mounted on the upper member and interengageable with the mandrel and said lower member to rotate said lower member in a direction opposite to the direction of rotation of the

mandrel upon actuation of said casing-engaging means, and gear means carried by said lower member and releasably interengageable with said lower member and said mandrel to rotate said lower member in the direction of rotation of the mandrel upon release of said casing-engaging means.

5. A reversing tool comprising, a tubular mandrel, means connecting the mandrel in fluid flow communication with an operating string for rotation with the string, an upper tubular member rotatably carried by the mandrel, a lower tubular member in communication with the mandrel, means rotatably connecting said members, casing-engaging means on the upper member, means on the upper member operable by the pressure of fluid in said mandrel to actuate said casing-engaging means into engagement with a surrounding well casing to anchor said upper member against rotation in the casing, means interengageable with said mandrel and lower member and operable by rotation of the mandrel to rotate said lower member in a direction opposite to the direction of rotation of the mandrel upon actuation of said casing-engaging means, means slidable in said lower member and movable to a position in interengagement with said lower member and said mandrel to cause said lower member to rotate in the direction of rotation of the mandrel upon release of said casing-engaging means and to another position out of engagement with said mandrel, and yieldable means engageable with said lower member and said slidable means to hold said slidable means in interengaging position.

6. A reversing tool comprising, a tubular mandrel, means connecting the mandrel in fluid flow communication with an operating string for rotation with the string, an upper tubular member rotatably carried by the mandrel, a lower tubular member in communication with the mandrel, means rotatably connecting said members, casing-engaging means on the upper member, means on the upper member operable by the pressure of fluid in said mandrel to actuate said casing-engaging means into engagement with a surrounding well casing to anchor said upper member against rotation in the casing, means interengageable with said mandrel and lower member and operable by rotation of the mandrel to rotate said lower member in a direction opposite to the direction of rotation of the mandrel upon actuation of said casing-engaging means, slidable means in said lower member movable into and out of a position in interengagement with said lower member and said mandrel and operable by the mandrel when interengaged therewith to cause said lower member to rotate in the direction of rotation of said mandrel, and means yieldingly engageable with said lower member and said slidable means to urge said slidable means toward said position, said slidable means being movable out of said position under the influence of the pressure of fluid in said mandrel.
